United States Patent Office

Des. 202,256

Patented Sept. 14, 1965

202,256

DICKEY FOR TRYING ON SUITS

James S. Moran, Jr., Maplewood Lane, Northford, Conn.

Filed May 19, 1964, Ser. No. 80,052

Term of patent 3½ years

(Cl. D3—26)

The figure is a front perspective view of a dickey showing my new design with the neck tie being printed thereon, the thickness of the dickey being uniform throughout.

I claim:

The ornamental design for a dickey for trying on suits, as shown and described.
